(57) **CLAIM**

The ornamental design for a sample container rack, as
shown and described.

DESCRIPTION

The present application is also related to U.S. Design patent
application Ser. No. 29/554,966, also entitled Sample
Container Rack and filed on Feb. 17, 2016, as well as U.S.
Design patent application Ser. No. 29/554,968, also entitled
Sample Container Rack and filed on Feb. 17, 2016, the
disclosures all of which are incorporated herein by reference.

FIG. 1 is a front perspective view of a sample container rack
according to our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate unclaimed environmental struc-
ture and form no part of the claimed design. The dash-dot-
lines are boundary lines that form no part of the claimed
design.

1 Claim, 5 Drawing Sheets
